(57) **CLAIM**

The ornamental design for a pillow, as shown and described.

DESCRIPTION

FIG. 1 is a front, top and left-side-perspective view of the pillow;

FIG. 2 is a top-plan view thereof;

FIG. 3 is a right-side-elevational view thereof, and wherein the left side is a mirror image of the right side;

FIG. 4 is a front-elevational view thereof;

FIG. 5 is a rear-elevational view thereof; and,

FIG. 6 is a bottom-plan view thereof.

The broken lines shown in the drawings are shown for illustrative purposes only and form no part of the claimed design. In addition, the surface shading illustrated in the drawings is provided merely to highlight the contour of the design.
